UNITED STATES PATENT OFFICE.

JOHN F. MAINS, OF JEFFERSONVILLE, OHIO, ASSIGNOR OF ONE-HALF TO
CHARLES W. GRAY, OF SAME PLACE.

ROLLER-SKATE.

SPECIFICATION forming part of Letters Patent No. 336,579, dated February 23, 1886.

Application filed September 28, 1885. Serial No. 178,339. (No model.)

To all whom it may concern:

Be it known that I, JOHN F. MAINS, a citizen of the United States, residing at Jeffersonville, in the county of Fayette and State of Ohio, have invented certain new and useful Improvements in Roller-Skates; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to roller-skates, and more particularly to improvements in the self-adjusting parts of the skate-hangers, also in the oiling devices, as set forth in the specification, and more particularly pointed out in the claims.

Figure 1 is a side elevation of a roller-skate with my improvements embodied therein. The front hanger and truck are shown in vertical longitudinal section. Fig. 2 is a cross-section of the hanger. Fig. 3 is a longitudinal section of the detachable oil-tube and elastic washer, the latter being shown in the position it occupies when the screw-plug is adjusted inward to a considerable distance.

A is the foot-plate of the skate, which may be wood or metal. The bracket or stationary portion B of the hanger is screwed to the under side of the foot-plate at the front and rear ends of the latter, and the pivoted portion C has its front and rear ends pivoted to the part B, the axial line of the bearings being inclined in the usual manner. The part C, as will be noticed by reference to Fig. 2, is of nearly triangular cross-section, being made thick and strong to give a firm and solid fastening to the post a, which secures the two parts B and C together. This post extends centrally through the frustum-shaped rubber spring b, and has a broad washer, c, and a screw-thread on its lower end, which enters the triangular part of C, as before stated. To adapt the stationary part B for the inverted-frustum-shaped spring b, it is formed with a cup-shaped cavity, c', having side walls which retain the spring between them.

The foot-plate A in Fig. 2 is shown in dot-

ted lines to illustrate the movement by which the spring is operated. When the foot-plate is inclined, as shown in this figure, the wall of the cup c' presses against the spring b, as seen on the left side, compressing it against the post a, and when the pressure is released the spring again recovers its normal shape, this movement being essential in allowing the operator to describe curves, &c., and for which various kinds of springs have been used. In this form of spring the advantage of rotary adjustability is apparent. As the spring may be worn by pressure against the central post, a, it can be partially rotated by simply loosening the screw-post and turning it with the thumb and fingers, so as to bring a new part in contact with the side walls of the cup c', thus allowing it to be used for a greater length of time. The hanger C is pivoted in reverse order at the front and rear ends, a' and b', to the bracket or fixed part B, as seen in Fig. 1.

The lubricating device consists of a large hollow screw, F, having a milled head, (so as to be easily operated by the fingers,) and a thick elastic collar or washer, i, of rubber, under the head. This screw is threaded only at the upper end, its lower end being snugly fitted into the hole e, leading centrally through the hangers C, as seen at front and rear in the view Fig. 1. In applying the oil a portion is first poured into the hole e (which latter leads to the axle f) to fill it to the lower end of the hollow screw F when the latter is inserted. The chamber e' in the screw F is then filled and the latter screwed into its place. The chamber e' retains the oil to a certain extent, (as the parts are air-tight,) and allows the oil to gradually find its way to the axle, thus preventing waste. When more oil is required, a slight turn is given to screw F, (and the collar i compressed thereby,) thus forcing the oil to the axle. The collar i prevents any escape of oil at the top of e, and also serves to retain the screw F in adjustment. The oil-hole e is inclined in the same direction with the axial line of hanger C, and extends inward from the front and rear of the two respective hangers, as seen in the view Fig. 1.

I do not claim, broadly, the combination, with the pivot-post of a skate-truck, of a rubber

cushion acting as a lateral spring upon said pivot, as I am aware that such a combination is old.

I claim as my invention—

1. The combination, in a roller-skate truck, of the bracket B, the hanger C, rocking thereon, a post, *a*, secured to the hanger and oscillating in the bracket, a rubber cushion, *b*, surrounding the post, and the cup *c'*, having side walls, to effect, in conjunction with the post, the lateral compression of the cushion, and having openings to permit of a compensating longitudinal expansion of the cushion, substantially as set forth.
2. In a roller-skate, the combination, with

the hanger having a bearing for the roller-
axle and an oil-duct, *e*, leading to said bearing, of a hollow screw-plug, F, longitudinally
adjustable in said duct, and the thick elastic
rubber collar *i* at the opening of the duct, and
compressible and laterally expansible by the
longitudinal adjustment of the plug, substan-
tially as set forth.

In testimony whereof I affix my signature in
presence of two witnesses.

JOHN F. MAINS.
